[57] CLAIM

The ornamental design for a cleated sole, as shown and described.

DESCRIPTION

FIG. 1 is a bottom plan view of a cleated sole showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a bottom plan view of a cleated sole showing a modified form of our new design;

FIG. 7 is a right side elevational view thereof;

FIG. 8 is a left side elevational view thereof;

FIG. 9 is a front elevational view thereof;

FIG. 10 is a rear elevation view of FIG. 6; and,

The top plan views of both embodiments are ornamenteally obscured by the upper portion of the shoe, but are smooth and unbroken.

The broken line showing of a shoe upper in FIGS. 2 and 7 is for illustrative purposes only and forms no part of the claimed design.
